UNITED STATES PATENT OFFICE.

ELDRIDGE R. BOYLE, OF WASHINGTON, DISTRICT OF COLUMBIA.

BATHING COMPARTMENT.

Application filed March 26, 1923. Serial No. 627,824.

This invention relates to toilet or bath facilities which are intended to be incorporated in bed rooms of hotels, dormitories, clubs and the like. The demand for accommodations in 5 hotels and rooming houses is uniformly for bed rooms with adjoining toilet and bath facilities. In supplying this demand there has been found difficulty in designing a bath room in conjunction with a bed room without sacrificing 10 large spaces and entailing considerable expense. This is particularly important where the demand is for a room of moderate costs but with adequate appointments for comfort and sanitary convenience. In particular, travelers and transient guests do not 15 demand the luxury in appointments which is the characteristic of hotel rooms of the better class.

Specifically my invention seeks to provide 20 in conjunction with a bed room, toilet and bath facilities so arranged as to provide a maximum of comfort and convenience with a minimum of lost space and expense of installation.

25 In carrying out my invention I have devised a compartment in which are arranged a toilet seat or water closet and also the requisite facilities necessary for shower baths.

It is one of the objects of my invention to 30 provide these facilities capable of convenient independent use without the presence of either hampering the use of the other. In fact it has been found that the covered water closet is extremely useful and desirable as a seat 35 during the use of the compartment for a shower bath. At the same time the compartment is adapted to be easily maintained in a cleanly condition.

Other advantages arising from my invention 40 will be evident from the following description. For purposes of illustration I have shown in the drawings one form in which my invention may be embodied, it being evident that numerous changes in proportion and minor details may be carried out 45 without departing from the scope of my invention.

In the drawings

Fig. 1 is a plan view of a room embodying 50 my invention, and

Fig. 2 is a vertical elevation taken on the line 2—2 of Fig. 1.

The room 3 as shown in the drawings is 55 designed to provide space for such articles of furniture as are necessary in a modest bed room adapted for the limited needs of a trav-

eler or similar occupant. These articles of furniture have been schematically indicated by dotted lines merely for the purpose of showing the relation between them and the 60 toilet compartment which is incorporated within the walls of the room.

The compartment 4 is formed by the outer wall of the room and the two intersecting partitions 5 and 6, the latter having a door indicated diagrammatically at 7. A water-proof curtain 8 is adapted to be drawn across the opening of the door. The rear wall of the compartment 9 separates the compartment 4 from the duct 10 which is adapted to carry 70 the necessary plumbing and vents. This duct 10 is common to the two adjacent rooms 3.

The floor 11 of the compartment 4 contains 75 a drain 12 to which point the different portions of the floor 11 slope gently. This drain 12 as shown on Fig. 1 is much nearer the wall 5 than the wall 9 to cooperate with the shower attachment to be later described. This floor 80 is preferably of tile or other water-proof construction customarily adapted for shower bath compartments. In like manner the inner surfaces of the walls of the compartment are water-proof.

85 Mounted in the wall of the room above the drain 12 are faucets 13, 13 having a common outlet 14 to which is attached a flexible tube 15. This tube terminates in a spray nozzle 16 adapted to be held in inverted position by a bracket 17 which in turn is mounted on the 90 wall. The length of the tube 15 and the position of the bracket 17 are such that the spray 95 may be projected from the wall bracket or may be used as a hand implement at the option of the bather.

It will be noted that both the shower attachment and its drain are localized at one end of the compartment and directly opposite the curtain door-way. Thus there is provided sufficient space in which the bather may 100 stand during the use of the shower.

At the opposite end of the compartment and mounted against the wall 9 is a water closet 18 the base of which is preferably independent of the floor 11. This water closet is 105 of the ordinary type but preferably will be attached directly to the wall 9 so that the floor 11 is clear and can be readily cleaned. A cover 19 is hinged at 20 to the flange 21. This flange 21 is attached to the wall 9 above the 110 water closet 18. The member 19 has a depending flange 22 of sufficient extent to pro-

tect the under surface of the member 18 from the splash or spray of the nozzle 16. The cover 19 and its attaching fixture 21 are, of course, constructed of water-proof material.

5 During the use of the water closet the cover 19 is lifted out of the way in the usual manner.

However, when the shower bath is being used the cover 19 prevents the water closet fixture from becoming wet or soiled from the 10 bath water. Also it frequently happens that the bather desires some sort of support during bathing. For example, if he desires a foot 15 bath, the cover 19 lends itself readily as a water-proof seat. The position of the cover 19 is well adapted while the bather is seated on the cover to bring his feet above the drain and beneath the shower jet whether the same 20 is operated from the wall bracket or by the hand of the bather. At the same time the cover 19 protects the seat of the water closet. If at a later time, it is intended to use the 25 water closet, it will be found still in good condition and without having been affected by the use of the shower in the same compartment.

An arrangement such as has been above described is of evident advantage in the economical construction of rooms for hotels, rooming houses and the like. There is a minimum of space used but at the same time there is no sacrifice in utility and convenience. Furthermore, the use of either the water 30 closet fixture or the shower bath fixture is independent of the presence of the other. It is desired to point out however, that in the use of the shower bath fixture, the juxtaposition of the water-proof cover for the water closet to be used as a bather's seat, is a material advantage.

40 While one form of this invention has been described and illustrated, nevertheless it is to be considered merely by way of example and not in any way limiting the invention beyond the scope of the appended claims.

45 What I claim is:

1. In a compartment, an apparatus therein 50 delivering a bath shower over a portion of the area of the compartment, and a water closet fixture in the compartment having a flanged water-proof cover adapted to be used as a bather's seat.

2. In a compartment, an apparatus on one 55 interior wall thereof, delivering a bath shower over a portion of the area of the compartment, a drain in the floor of the compartment beneath the shower apparatus, and a

water closet fixture in the compartment having a flanged water-proof cover adapted to be used as a bather's seat.

3. In a compartment, an apparatus on one 60 interior wall thereof, delivering a bath shower over a portion of the area of the compartment beneath the shower apparatus, and a water closet fixture in the compartment removed from the normal path of the shower, 65 said fixture having a flanged water-proof cover adapted to be used as a bather's seat.

4. In a compartment having a doorway in one wall, an apparatus in said compartment 70 delivering a bath shower over a portion of the compartment immediately opposite the doorway, a drain in the floor of the compartment beneath the shower apparatus, and a water closet fixture in the compartment remote from 75 the doorway and having a water-proof cover adapted to be used as a bather's seat.

5. In a combination, a compartment, a shower apparatus on one wall thereof, a drain in the floor of said compartment beneath the 80 shower apparatus, a water-closet having a circumferentially flanged water-proof cover adjacent one wall of the compartment and spaced from said shower apparatus.

6. In combination, a compartment having 85 a doorway along one of the side walls thereof, a shower apparatus on the other side wall and opposite the doorway, a drain in the floor between the doorway and said apparatus, toward which drain the floor slopes, and a water closet arranged in said compartment at one side of said shower apparatus.

7. In a compartment, an apparatus therein 90 delivering a bath shower over a portion of the area of the compartment, a water closet fixture in the compartment removed from the normal path of the shower and a cover hinged to said fixture and having a flange extending downwardly over the sides of the fixture.

8. In a compartment, an apparatus therein 100 delivering a bath shower over a portion of the area of the compartment, a water closet fixture mounted on one wall of the compartment removed from the normal path of the shower, a cover hinged to said fixture and having a flange extending downwardly over the sides of the fixture, and a drain in the floor of the compartment beneath the said apparatus and to which drain the floor slopes.

105 In testimony whereof, I have hereunto af-
fixed my signature.

E. R. BOYLE.
